(57) **CLAIM**

The ornamental design for a knife, as shown and described.

DESCRIPTION

FIG. 1 is a front-left top perspective view of a knife according to our new design;

FIG. 2 is a rear-left top perspective view thereof;

FIG. 3 is a front-left bottom view thereof;

FIG. 4 is a rear-left bottom view thereof;

FIG. 5 is a left-side view thereof;

FIG. 6 is a right-side view thereof;

FIG. 7 is a front view thereof;

FIG. 8 is a rear view thereof;

FIG. 9 is a top plan view thereof; and,

FIG. 10 is a bottom plan view thereof.

Conventional shading is illustrated for purposes of highlighting the line drawings, but forms no part of the claimed design.

The broken line showing of portions of the knife is included for the purpose of illustrating environmental structure and forms no part of the claimed design.
